UNITED STATES PATENT OFFICE.

JOHN D. ROBILOTTO, OF NEW YORK, N. Y.

TOY GUN.

1,277,480.

Specification of Letters Patent.

Patented Sept. 3, 1918.

Application filed October 29, 1917. Serial No. 199,102.

To all whom it may concern:

Be it known that I, JOHN D. ROBILOTTO, a citizen of the United States, residing at New York, in the county of New York and State 5 of New York, have invented certain new and useful Improvements in Toy Guns, of which the following is a specification.

This invention relates to toys, and more particularly to a toy gun for exploding 10 blank cartridges, torpedoes, and similar explosive articles.

In using the ordinary sticks or canes for exploding torpedoes and similar devices the force of the explosion is exerted axially of 15 the cane and, due to this fact, many persons have been injured when using these devices due to an unusually heavy charge of explosive which tends to drive a cane upward with great force. One of the main objects 20 of the invention is to provide a device of the character stated so constructed that the force exerted by the explosive will be along lines which are transverse to the axis of the handle of the device thus eliminating danger 25 of injury to the user by the handle being driven back by the force of the explosive into the user's hand. A further object is to provide a device of this character which may be quickly and easily constructed at small 30 cost. A still further object is to provide a device having a handle and a head secured at one end thereof, this head being so shaped as to provide a reduced striking end which 35 will insure proper explosion of a cartridge placed therein. Further objects will appear from the detailed description.

In the drawings:

Figure 1 is a side view of an exploding device constructed in accordance with my 40 invention.

Fig. 2 is a plan view of the striking end.

Fig. 3 is a central longitudinal section through the head.

The head 1 is of substantially cylindrical 45 shape for approximately $\frac{2}{3}$ of its length, and is tapered toward one end to provide a frusto-conical striking end 2. This head is provided with an axial bore 3 extending the full length thereof, this bore corresponding 50 approximately in diameter to the exterior diameter of a cartridge of suitable caliber, such as the commonly used twenty-two cali-

ber cartridge. When this cartridge 4 is inserted into the lower end of the striking point 2, the flange of the base or head of the 55 cartridge is positioned closely adjacent the outer end of point 2, being a short distance from the peripheral edge thereof. By striking the head of the cartridge 4 against any suitable fixed object such as a curb-stone, 60 pavement, or a similar object, the cartridge will be exploded, the gases resulting from the explosion being discharged through the bore 3.

A short rod 5 is fixedly secured in head 1. 65 This rod is fastened in a handle 6 of suitable length, a ferrule 7 being driven on the inner end of the handle to prevent splitting or spreading thereof. Preferably the handle 6 is of such length as to have the head 1 a 70 considerable distance from the user when the cartridge 4 is exploded thus avoiding danger of injury from the explosion. By this construction, the force of the explosion is exerted along lines at right angles to the 75 handle 6. This eliminates all danger of injury due to the handle being driven toward the user in the case of an explosion of unusual force. It will be evident that this device may also be used for exploding torpedoes, and similar explosive articles, as well 80 as for blank cartridges, and I do not desire to in any way limit its use to this one particular article.

What I claim is:

1. In a device of the character described, 85 a handle, and a head carried at one end of the handle and disposed at right angles thereto, said head being provided with an axial bore extending the full length thereof 90 for the reception of a cartridge to be exploded, said bore serving to permit easy escape of the gases generated by the explosion of the cartridge and also facilitating removal of the empty cartridge from the 95 head in the event that the cartridge sticks in the head.

2. In a device of the character described, 100 a handle, and a head secured to one end of said handle and disposed at right angles thereto, said head being provided with an axial bore extending the full length thereof and having one end portion outwardly tapering to provide a reduced striking end adapt-

ed to engage the peripheral flange of the head of a cartridge so as to cause explosion of the charge contained thereby when the cartridge is struck against an object, the 5 bore permitting easy escape of gases generated by the explosion and facilitating removal of the cartridge from the head.

In testimony whereof I affix my signature in presence of two witnesses.

JOHN D. ROBILOTTO.

Witnesses:

FRANK MARZOCCIA,
JAMES J. DEPELL.
